UNITED STATES PATENT OFFICE.

ALBERT C. FORD, OF CHICAGO, ILLINOIS.

DESIGN FOR AN ADVERTISING SIGN.

Application filed June 5, 1924. Serial No. 9,799. Term of patent 7 years.

To all whom it may concern:

Be it known that I, ALBERT C. FORD, a citizen of the United States, residing at Chicago, in the county of Cook and State of Illinois, have invented a new, original, and ornamental Design for Advertising Sign, of which the following is a specification, reference being had to the accompanying drawing, forming part thereof.

The figure is a plan view of an advertising sign, showing my new design.

I claim:

The ornamental design for an advertising sign, as shown.

ALBERT C. FORD.
